MEANS FOR POSITIONING CORE BARS IN
HORIZONTAL PIPE CASTING APPARATUSJohn Elijah Goates, Provo, Utah, assignor to
Pacific States Cast Iron Pipe Co., Provo, Utah,
a corporation of Nevada

Application June 5, 1943, Serial No. 489,822

12 Claims. (Cl. 22—1)

The invention relates generally to the art of casting pipe in a horizontal position and primarily seeks to provide novel means for placing the cores in the flasks so that they will be perfectly centered within the molding surfaces at the time the castings set by the solidification of the molten metal, thereby to assure perfect uniformity in thickness of the cast wall structures and avoid the wastage of metal heretofore experienced because of the prior necessity of providing sufficient tolerances in wall thicknesses to assure the provision of minimum acceptable metal thickness at all points regardless of any off center positioning of core parts within said molding surfaces.

For many years it was considered impractical if not commercially impossible to cast pipes and similar cylindrical articles horizontally, i. e., with the axis of the mold and core disposed substantially in a horizontal plane. This was due principally to the fact that in prior attempts to cast such articles horizontally it was considered necessary to employ chaplets for holding the core "centered" with respect to the mold cavity, and these chaplets, being cast into the pipe or other article, resulted in the formation of leakage spaces between the stems of the chaplets and the metal cast around the stems. Chaplets were employed in order to prevent deflection of the core or core bar due to several different forces, viz., the weight of the core or core bar, the substantially lateral pressure on the core exerted by the velocity pressure of the stream of metal entering the mold, the unequal expansion of the top and bottom portions of the core bar resulting from the bottom of the bar being heated before the top thereof during filling of the mold from the bottom up, and the upward vertical force due to the natural buoyancy of the core in the molten metal.

Prior to the present invention apparatus has been devised for initially fixing the positions of the cores in the flasks so that at the midpoint in the length of each core the core bears an eccentric relation within the molding surfaces, the degree of eccentricity being estimated in an amount equal to and in directions opposite from the anticipated movement of the core upwardly and laterally under the influence of the poured molten metal. An example of a prior art disclosure of such apparatus is to be found in U. S. Letters Patent 2,042,907 issued to James R. McWane on June 2, 1936. Such improved casting apparatus has been very beneficial and has brought about marked advances in the art but also has been limited in efficiency in attaining the desired end of providing cast pipe having uniform wall thickness throughout and which is cast with a minimum of waste. For example, the actual movements of the cores when the mold is poured is seldom exactly equal to the anticipated movements for which the cores have been initially set.

Several conditions may be encountered which will bring about movement of one or more cores from their initial setting such as will result in the casting of pipe with non-uniform wall thicknesses. 5 For instance, after the cores are set in the drag of the flask in the initial position expected ultimately to result in placement in perfect centered relation in the flask, placing of the cope on the drag very often causes one or more of the cores to move as much as .05", and clamping the flask drag and cope together and the transferring of the flask to the pouring floor also often causes the cores to move out of their initially set positions. Prior to the present time no practical means has been devised to detect and measure this movement of cores from their initially set positions. It is therefore an object of the present invention to provide novel means for detecting and measuring movement of the cores from their initially set positions, and said invention comprehends not only the provision of this novel core bar movement measuring means but also the combination thereof with means for adjusting the positions of the core bars so that when movement of core bars out of their initially set positions is detected, the adjusting means and the measuring means can be used in combination to effect adjustment of core bars during and immediately after pouring of the molten metal, thereby to assure attainment of the desired perfectly centered relation of the cores 15 within the molding surfaces in the flask just prior to solidification of the molten metal.

In its more detailed nature the invention resides in providing a novel core bar deflection gauge comprising a rigid lever insertible into the open end of a core bar and having provision at its inserted end to engage internally in the core bar intermediately of the ends thereof and be positioned by said contact, and of a length for projecting a considerable distance beyond one end of said core bar, said extended end resting upon a fulcrum inwardly of its extended end extremity, and gauge means being provided and engaged by said lever adjacent its extended end extremity for indicating the degree of displacement of the opposite end of the lever by reason of its contact in the core bar and as a result of deflection of the core bar from its initial setting in the flask.

Another object of the invention is to provide in 20 a gauge equipment of the character stated a novel mounting for a gauge set comprising two gauge units each equipped with a lever end contacting spring plunger, one said unit being placed for actuation by movement of the lever end laterally and the other being placed for actuation by movement of the lever end vertically.

Another object of the invention is to provide 25 a gauge equipment of the character stated in combination with means on the flask for supporting and accurately positioning the cores

therein and which include threadably mounted devices adjustable to engage and bend the cores to provide the desired amount of deflection therein in the initial setting of the cores in the flask and also for readjusting the initially set deflection in said cores should the gauge equipment reveal that the initially set core deflection has been disturbed by closing or moving of the flask, or has been improperly selected and must be altered following the pouring of the mold and before the molten metal solidifies in order to provide for the necessary perfect centering of the cores in the finished casting.

With the above and other objects in view that will hereinafter appear, the nature of the invention will be more fully understood by following the detailed description, the appended claims and the several views illustrated in the accompanying drawings.

In the drawings:

Figure 1 is a plan view illustrating the invention, parts being broken away and the cope of the flask being removed.

Figure 2 is a side elevation illustrating the apparatus shown in Figure 1.

Figure 3 is a left end elevation on the apparatus illustrated in Figure 1.

Figure 4 is an enlarged fragmentary vertical cross section illustrating the contact of a gauge lever in one of the hollow cores intermediate the ends thereof.

Various forms of casting flask structure may be employed in practicing the invention and in the example of embodiment of the invention herein disclosed the flask structure includes a drag 5 and a cope 6. Each drag and cope includes spaced end walls 7 and 8 having clearances 9 therein in which to receive the multiple of hollow core bars generally designated 10 which are arranged side by side in the flask in the manner clearly illustrated in Figures 1 and 3 of the drawings.

Each core bar includes a bell end 11 and a spigot end 12, and when positioned in the flask in the manner illustrated in Figure 1 the core sand on the cores and the molding sand in the flask cavities cooperate to provide between them suitable cavities 13 in which the pipes are cast, each said pipe being formed with a bell portion 14 at one end and a spigot portion 15 at its other end. Each cope and drag also is provided with a central end projection 16 at each end for receiving crane tackle in a manner for facilitating handling of these heavy casting apparatus units. The cope and drag sections 5 and 6 are clamped together in superposed relation by the usual clamps 17 in the manner clearly illustrated in Figures 2 and 3, and during the actual pouring of the mold the flask structure may rest firmly on end supports generally designated 18. Suitable antifriction roller equipments 19 are provided intermediately of the end supports 18 and facilitate movement of the flask structure into position at the pouring station.

Each drag section 5 is provided with longitudinally spaced sets of side lugs 20 and 21 at each end thereof in position for receiving the respective bell and spigot ends 11 and 12 between the lugs 20 of each set. Adjuster screws 22 are threaded through the lugs 20 and 21 so as to engage inwardly against the sides of the respective core bell and spigot ends 11 and 12 in the manner clearly illustrated in Figure 1.

A single endwise extending lug 23 is provided at each end of the drag section 5 in position for extending beneath the respective ends of each

core bar 10, and a single adjuster screw 24 is directed upwardly through each lug 23 in position for engaging upwardly against the overlying core bar end. A yoke 25 is removably mounted over each core bar end 10 or 11 intermediately of the associated, longitudinally spaced sets of adjuster screw lugs 20 and 21 in the manner clearly illustrated in Figure 1, the arms of each yoke being anchored against upward movement as at 26. The yokes serve the purpose of resisting upward movement of the core bars from their adjustable supports or mountings comprising the underlying adjuster screws 24 and the horizontally inwardly directed adjuster screws 22, and each yoke is equipped with a downwardly directed adjuster screw 27 which engages the upper surface of the respective end of the associated core bar.

It will be obvious from the foregoing that by 20 a proper adjustment of the vertically directed adjuster screws 24 and 27 the individual core bars can be bent or deflected upwardly or downwardly at the central portions thereon, or intermediate their ends, and by properly adjusting the horizontally inwardly directed adjuster screws 22 bending of the core bars in the horizontal direction can be accomplished in similar manner.

The structure described hereinabove is well known in the art and an example of this type of equipment is disclosed in U. S. Letters Patent 2,042,907 issued to J. R. McWane on June 2, 1936, and such apparatus forms no part of the present invention except in combination with the core bar deflection detecting and indicating equipment soon to be described. By utilizing the adjustable core supporting and positioning equipments hereinbefore described by properly adjusting the devices 22, 24 and 28 included therein, the core bars can be bent or deflected in 30 the initial assembling of the flask or mold so as to place the central or intermediate portions of the core bars eccentrically in the flask structure in anticipation of the known effect of the inpouring molten metal to lift the central portions 35 of the core bars and also to laterally deflect said portions. By thus initially setting the central portions of the core bars below the axis of the mold by an amount equal to the anticipated rise of the core when the mold is poured, and also to one side toward the inpouring molten metal by an amount equal to the anticipated lateral deflection of the core when the mold is poured, it is possible to approximate a perfect centering of the core bars in the metal of the cast as it solidifies 40 in the molding cavities. It is the purpose of the present invention to provide a gauging equipment by which it is possible to accurately determine the degree of deflection of the core bars, and also to accurately determine the amount of deflection actually caused by the inrushing molten metal during the pouring of the mold so that the core bending devices hereinabove referred to can be employed while the pouring of the mold is in progress and before the molten metal solidifies so as to absolutely assure perfect 45 centering of the core bars in the finished castings and the provision of casting walls of uniform thicknesses throughout without the necessity of providing tolerances which would result in the use of an unnecessarily large amount of metal in order to provide the desired strength in the finished pipe throughout the length thereof. The improved gauging equipment includes frame uprights 28 which serve as a support for a transversely disposed pouring platform P which may 50 55 60 65 70 75

serve as a support for an operative in charge of the mold pouring activities. The uprights 28 also serve as supports for a horizontally and transversely disposed shelf S from the inner edge of which upwardly projects a knife edge fulcrum bar 29 which preferably extends across the full width of the flask structure so as to be common to all of the multiple of cores mounted therein.

The uprights 28 also support an uprightly positioned channel beam 30 which is disposed above and to one side of and parallel the shelf S. The beam 30 serves as a support for a plurality of brackets 31, one such bracket being provided for cooperating with an individual gauge equipment associated with each core bar. Each bracket includes an inverted U-shaped portion 32 which embraces the upper extremity of the beam 30 in the manner clearly illustrated in Figure 2, and adjuster screws 33 extend downwardly through the base of the U and against the upper extremity of the beam for vertically-adjustably mounting the respective bracket on said beam. Each bracket is clamped to the beam by a clamping screw 34 and includes a removable bottom clamp plate 35 which may be removed so as to permit removal of the respective bracket from the beam 30. Each bracket also includes a central depending leg 36 on which a standard Starrett gauge 37 is tiltably mounted as at 38. The gauge 37 includes a spring projected actuated plunger 39. Each bracket also includes a lateral depending leg 40 including a horizontal foot portion 41 on which a second standard Starrett gauge 42 is tiltably mounted as at 43, the gauge units 37 and 42 together forming a gauge set. Each gauge 42 also includes a spring projected actuator plunger 44.

A rigid gauge lever 45 is associated with each core bar and is extended in the manner illustrated in Figures 1 and 2 of the drawings through the adjacent open end of the respective core bar into position for having the spider 46 which is welded or otherwise secured to the inner end thereof engage with the internal wall of said core bar near the central portion thereof, that is intermediate the ends of the core bar. The spider 46 may be shaped in any approved manner and in the present disclosure takes the form of a simple inverted U piece disposed to have the extremities of the U legs engage the central portion of the core bar so that any movement of the central portion of the core bar will be imparted to the engaging gauge lever end and be transmitted to the outer end portion of said lever which extends from the open end of the respective core bar.

The outer ends of the levers 45 which project beyond the open ends of the core bars extend over and rest upon the common fulcrum bar 29, and the end extremities of said levers beyond the fulcrum bar extend between and engage the actuator plungers 39 and 44 of the respective gauge unit sets in the manner clearly illustrated in Figure 3 of the drawings. Each lever may have an inverted U piece 47 welded or otherwise secured thereto at the position of the associated gauge units 37 and 42, the flat top of the U piece serving as a flat surface with which the vertically and downwardly directed plunger 39 can engage, and one upright leg of the U piece serving as a flat surface against which the horizontally directed actuator plunger 44 projects. With the parts related in the manner described and clearly illustrated in Figure 3, one gauge unit 37 will serve to detect and indicate any movement of the lever end in a vertical direction, either up or

down, and the other gauge unit 42 will indicate lateral movement of the lever end in either direction. Any movement of the lever end other than strictly vertical or lateral will indicate a certain amount on both gauges. The gauges used are the common dial type employing an indicating hand actuated by a spring projected plunger. The spring which projects each plunger acts against the plunger so that if unrestrained the plunger will move to its outer limited position. Each actuator plunger is held against the associated lever end by the plunger projecting spring and any movement of the plunger in or out will result in the provision of a deflection indication on the respective gauge dial.

Before closing the flask or mold, the cores are set to the predetermined positions in the usual manner as hereinbefore described, the central portion of each core being bent to an eccentric position in the molding cavity, slightly below the axis of the cavity in anticipation of the lifting effect of the inrushing molten metal, and to one side of said axis toward the direction of the pour in anticipation of the lateral deflection resulting from the inpouring of the molten metal. After the flask has been closed and moved to the pouring station the deflection gauging equipments can be mounted in the manner illustrated in Figures 1, 2 and 3 of the drawings in order to detect and indicate core bar deflection during the pouring of the mold. During the pouring of the mold, movement of the outer ends of the levers 45 will act on the gauge units 37 and 42 of the respective sets in a manner for indicating any movement of the deflection of the central portions of the cores, since any radial movement of the ends of the levers may be resolved into vertical and horizontal components, the gauges will indicate deflection in any direction. The movement of the gauge actuating end extremities of the levers being in exact proportion to the movement of the lever ends which extend into the core bars, depending on relative lever arm lengths, the gauges may be calibrated to indicate the exact amount of radial movement of each core bar at its mid point.

If the micrometer gauges show that the actual rise of a given core is more or less than the anticipated amount, the particular adjuster screw equipments 24 and 27 can be utilized to quickly adjust the core to the correctly centered position in the molding cavities before solidification of the metal in the molding cavity takes place. Similarly, any lateral radial adjustment of the core bars under like conditions can be effected by manipulation of the adjuster screws 22. Long handle ratchet wrenches 48 having reversible heads or sockets 49 can be utilized for turning the screw equipments in one direction or the other in effecting the desired bending adjustment of the core bars.

If desired, a suitable heat insulator jacket 50 can be provided on each lever 45 throughout the length of that portion thereof which is intended to lie within core bars and an additional portion thereof extending without the core bars so as to protect the lever from the effects of excessive heat within the cores.

By closely controlling the wall thicknesses of the cast pipe by use of the improved apparatus herein disclosed a considerable saving of metal will result because it is not necessary to make as great an allowance for tolerances in wall thicknesses as has been necessary heretofore, and

greater uniformity in wall thickness in the cast pipe is assured.

It will also be apparent that the apparatus herein disclosed can be employed to determine the most desirable core bar types and also the changes in the deflectional properties of core bars as the result of long use, exposure to high temperatures, or other abnormal conditions. By thus using the apparatus to detect an improper type of core bar, losses which would ultimately result from the use of such improper types of core bars can be entirely eliminated. Thus, by designing or selecting core bars which will test well and control well, better casting practice will result, also when the life of core bars has been spent, the herein disclosed detecting and indicating gauge equipment will make known the deficiency of the core bars so that their use can be discontinued.

It is of course to be understood that the details of structure and the arrangement of parts may be variously changed and modified without departing from the spirit and scope of the invention.

I claim:

1. In pipe casting apparatus, a flask structure, means for supporting a hollow core in said flask structure in position for internally shaping pipe castings, said core being open at at least one end, a gauge lever engaged at one end internally in said core at a point intermediate the ends thereof and extending at its other end through and beyond the open end of the core, and means for indicating the degree of movement of said extended end of the lever to in turn indicate the degree of deflection of said core intermediate its ends.

2. In horizontal pipe casting apparatus, a horizontal flask structure, means for supporting a hollow core horizontally in said flask structure in position for internally shaping pipe castings and including devices adjustably engageable with said core for bending it so as to dispose the portion thereof intermediate its ends eccentrically in said flask structure, and means including an element engageable in the core intermediate its ends for detecting and indicating changes in the degree of the eccentric positioning of said core intermediate portion which occur during the pouring of the mold.

3. In horizontal pipe casting apparatus, a horizontal flask structure, means for supporting a hollow core horizontally in said flask structure in position for internally shaping pipe castings and including devices adjustably engageable with said core for bending it so as to dispose the portion thereof intermediate its ends eccentrically in said flask structure in anticipation of and for the purpose of compensating for deflection of said core intermediate portion by contact of the molten metal at the time the mold is poured, and means including an element engageable in the core intermediate its ends for detecting and indicating the degree of deflection of said core intermediate portion during the pouring of the mold.

4. In horizontal pipe casting apparatus, a horizontal flask structure, means for supporting a hollow core horizontally in said flask structure in position for internally shaping pipe castings and including devices adjustably engageable with said core for bending it so as to dispose the portion thereof intermediate its ends eccentrically in said flask structure in anticipation of and for the purpose of compensating for deflection of

said core intermediate portion by contact of the molten metal at the time the mold is poured, and means including an element engageable in the core intermediate its ends for detecting and indicating the degree of deflection of said core intermediate portion during the pouring of the mold, said devices being readjustable under visual guidance of said detecting and indicating means for assuring perfect centering of said intermediate core portion in the flask just prior to solidification of the metal of the cast.

5. In horizontal pipe casting apparatus, a horizontal flask structure, means for supporting a hollow core horizontally in said flask structure in position for internally shaping pipe castings and including devices adjustably engageable with said core for bending it so as to dispose the portion thereof intermediate its ends eccentrically in said flask structure, said core being open at at least one end and said detecting and indicating means including a gauge lever engaged at one end internally in said core at a point intermediate the ends thereof and extending at its other end through and beyond the open end of the core, and means for indicating the degree of movement of said extended end of the lever to in turn indicate the degree of deflection of said core intermediate its ends.

6. In horizontal pipe casting apparatus, a horizontal flask structure, means for supporting a hollow core horizontally in said flask structure in position for internally shaping pipe castings and including devices adjustably engageable with said core for bending it so as to dispose the portion thereof intermediate its ends eccentrically in said flask structure in anticipation of and for the purpose of compensating for deflection of said core intermediate portion by contact of the molten metal at the time the mold is poured, and means for detecting and indicating the degree of deflection of said core intermediate portion during the pouring of the mold, said devices being readjustable under visual guidance of said detecting and indicating means for assuring perfect centering of said intermediate core portion in the flask just prior to solidification of the metal of the cast, said core being open at at least one end and said detecting and indicating means including a gauge lever engaged at one end internally in said core at a point intermediate the ends thereof and extending at its other end through and beyond the open end of the core, and means for indicating the degree of movement of said extended end of the lever to in turn indicate the degree of deflection of said core intermediate its ends.

7. In horizontal pipe casting apparatus, a horizontal flask structure, means for supporting a hollow core horizontally in said flask structure in position for internally shaping pipe castings and including devices adjustably engageable with said core for bending it so as to dispose the portion thereof intermediate its ends eccentrically in said flask structure, said core being open at at least one end and said detecting and indicating means including a gauge lever having a contact spider at one end thereof and said one end extended into the core so that said spider engages in the core intermediate the ends thereof and having its other end extended out through and beyond the open end of the core, a fulcrum rest for said lever disposed intermediately of the open end of the core and the outer end extremity of the lever, and gauge means engaging said lever

at an outer end portion thereof beyond said fulcrum rest and effective to indicate the degree of vertical and lateral movement imparted to the outer end of said lever by reason of the contact of said lever in the core intermediate the ends thereof and deflection of said intermediate core portion.

8. In horizontal pipe casting apparatus, a horizontal flask structure, means for supporting a hollow core horizontally in said flask structure in position for internally shaping pipe castings and including devices adjustably engageable with said core for bending it so as to dispose the portion thereof intermediate its ends eccentrically in said flask structure, said core being open at at least one end and said detecting and indicating means including a gauge lever having a contact spider at one end thereof and said one end extended into the core so that said spider engages in the core intermediate the ends thereof and having its other end extended out through and beyond the open end of the core, a fulcrum rest for said lever disposed intermediately of the open end of the core and the outer end extremity of the lever, and a pair of gauges each having a spring projected actuator plunger engageable with an outer end portion of the lever beyond said fulcrum rest one said plunger being disposed uprightly for indicating the degree of vertical movement imparted to the outer end of the lever by reason of the contact of said lever in the core intermediate the ends thereof and deflection of said intermediate core portion and the other of said plungers being disposed horizontally for in similar manner and by like reason indicating lateral movement of said lever outer end portion.

9. In horizontal pipe casting apparatus, a horizontal flask structure, means for supporting a hollow core horizontally in said flask structure in position for internally shaping pipe castings and including devices adjustably engageable with said core for bending it so as to dispose the portion thereof intermediate its ends eccentrically in said flask structure, said core being open at at least one end and said detecting and indicating means including a gauge lever having a contact spider at one end thereof and said one end extended into the core so that said spider engages in the core intermediate the ends thereof and having its other end extended out through and beyond the open end of the core, a fulcrum rest for said lever disposed intermediately of the open end of the core and the outer end extremity of the lever, a pair of gauges each having a spring projected actuator plunger engageable with an outer end portion of the lever beyond said fulcrum rest one said plunger being disposed uprightly for indicating the degree of vertical movement imparted to the outer end of the lever by reason of the contact of said lever in the core intermediate the ends thereof and deflection of said intermediate core portion and the other of said plungers being disposed horizontally for in similar manner and by like reason indicating lateral movement of said lever outer end portion, a single bracket supporting both gauges, and means tiltably mounting the gauges on said bracket.

10. In horizontal pipe casting apparatus, a horizontal flask structure, means for supporting a plurality of hollow cores horizontally and side

by side in said flask in position for internally shaping pipe castings, said means including devices adjustably engageable with each said core for bending it so as to dispose the portion thereof intermediate its ends eccentrically in said flask structure in anticipation of and for the purpose of compensating for deflection of said core intermediate portion by contact of the molten metal at the time the mold is poured, and means for detecting and indicating the degree of deflection of all said core intermediate portions during the pouring of the mold, said devices being readjustable under visual guidance of said detecting and indicating means for assuring perfect centering of each said intermediate core portion in the flask just prior to solidification of the metal of the cast, each said core being open at at least one end and said detecting and indicating means including a gauge lever associated with each core and having a contact spider at one end thereof and said one end extended into the particular core so that said spider engages in the core intermediate the ends thereof and having its other end extended out through and beyond the open end of the core, a fulcrum rest common to all said levers and disposed intermediately of the open ends of the cores and the outer end extremities of the levers, and gauge means engaging each lever at an outer end portion thereof beyond said fulcrum rest and effective to indicate the degree of vertical and lateral movement imparted to the outer end of the respective lever by reason of the contact of said lever in the core intermediate the ends thereof and deflection of the particular intermediate core portion.

11. Apparatus as defined in claim 10 in which each gauge means comprises a pair of gauge units, each unit having a spring projected actuator plunger engageable with an outer end portion of the respective lever beyond the common fulcrum rest, one said plunger being disposed uprightly for indicating the degree of vertical movement imparted to the outer end of the engaged lever by reason of the contact of said lever in the respective core intermediate the ends thereof and deflection of said intermediate core portion and the other of said plungers being disposed horizontally for in similar manner and by like reason indicating lateral movement of said lever outer end portion.

12. Apparatus as defined in claim 10 in which each gauge means comprises a pair of gauge units, each unit having a spring projected actuator plunger engageable with an outer end portion of the respective lever beyond the common fulcrum rest, one said plunger being disposed uprightly for indicating the degree of vertical movement imparted to the outer end of the engaged lever by reason of the contact of said lever in the respective core intermediate the ends thereof and deflection of said intermediate core portion and the other of said plungers being disposed horizontally for in similar manner and by like reason indicating lateral movement of said lever outer end portion, a support beam disposed transversely with respect to the outer ends of all of the levers, a single bracket vertically-adjustably mounted on the support beam adjacent the outer end of each lever, and means tiltably mounting each gauge unit of each unit pair on one of said brackets.

JOHN ELIJAH GOATES.
